UNITED STATES PATENT OFFICE.

GOTTLÖB HIMMEL, OF TUEBINGEN, GERMANY.

APPARATUS FOR CONTROLLING GAS-LAMPS.

No. 909,089.

Specification of Letters Patent.

Patented Jan. 5, 1909.

Application filed May 15, 1908. Serial No. 433,100.

To all whom it may concern:

Be it known that I, GOTTLÖB HIMMEL, a citizen of the German Empire, residing at Tuebingen, in the Kingdom of Würtemberg, 5 Empire of Germany, have invented certain new and useful Improvements in Apparatus for Controlling Gas-Lamps; and I do hereby declare the following to be a full, clear, and exact description of the invention, such as 10 will enable others skilled in the art to which it appertains to make and use the same.

This invention consists in improvements in apparatus for operating devices for controlling gas lamps from a distance, whereby a 15 part or all of the gas flames may be lighted and extinguished from any suitable central point in any desired series, at any desired moment by means of a pressure impulse in the gas duct.

The improved apparatus is applicable to 20 gas lamps in streets as well as in railway stations, factories and other localities where a large number of gas flames have to be lighted and extinguished at times. With such gas installations it is frequently required that a 25 part of the lamps shall be extinguished say about midnight, while the other part needs extinguishing only at dawn. This object is effected in the improved apparatus by means of a pressure impulse. In order that the 30 lighting device shall operate with absolute certainty, all the movable parts are guided positively, and no liquid seals, pinions, &c., are employed. The diaphragm is suitably weighted for the purpose of regulating at 35 will the pressure under which the apparatus is to work.

In the drawings, Figure 1 is an elevation partly in vertical section of the improved controlling apparatus applied to a device for 40 lighting gas flames at a distance, in which a cock is employed as the obturating member. Fig. 2 is an elevation partly in vertical section of the upper part of the lighting device, with a plug valve as the obturating member. 45 Figs. 3 to 5 are elevations illustrating three different positions of the operating mechanism shown separately. Fig. 6 is a plan view of the mechanism for operating the cock or the valve. Fig. 7 is a plan partly in horizontal section, of a further improved disk for 50 operating the valve.

The controlling mechanism serves to open or to shut off the supply of gas to the burners which are of ordinary construction, provided 55 with permanently pilot flames or other igniting means.

1 is a box containing a diaphragm 2 of leather or the like shown in its depressed position. Upon the diaphragm, 2, there rests a plate, 3, on which a vertical rod, 4, is mounted so as to be capable of being easily rotated. This rod extends through a guide part, 5, which also carries a rotating actuating device 6 (Figs. 3 to 5). To the upper end of the rod, 4, is fixed a disk, 8, fitted with a plurality of radial arms, 7, that vary in number according to requirements. This disk, 8, has a sleeve, 9, formed with a longitudinal slot, 10, in which is a cross pin 11 that is fixed on the round spindle, 12. This spindle, 12, thus 70 gears with the sleeve 9 and is fixed to the cock plug, 13 (Fig. 1) in the cock casing, 14. The plug, 13, is pressed by a spring, 19, on to its seat, and the spring and the plug are held together by a screw cap, 20. 75

14 is a head carried by the gas supply pipe, 15, branching from the screw fitting 16, that also carries the diaphragm box, 1. The gas is thus admitted under the diaphragm, 2, as well as to the cock, 13. In front of the cock, 80 13, there is a pipe, 17, through which gas is supplied to the pilot flame. Behind the cock, 13, there is a pipe, 18, which supplies the gas to the main flame of the burner. In Fig. 1, the gas supply is shown open to the 85 pipe, 18, namely to the main flame of the burner.

Now the present invention consists in producing rotation of the rod, 4, simultaneously with its upward movement. The spindle, 90 12, with the cock, 13, will be rotated through exactly the same angle as the rod. This rotation is effected by means of the operating device 6 located on the support, 5, and shown more fully in Figs. 3 to 5. 95

Fig. 3 shows the device in the position of rest, *i. e.*, at the end of the descent of the rod, 4. Two arms, 7, of the disk, 8, are engaged in recesses of the operating part, 21, that is mounted on a pivot, 26, on the support, 5, (Fig. 1) and is provided with a tipping weight, 28. Above this part, 21, is a lever 22, which is pivoted at, 27, and is provided with a tipping weight, 29. A stop, 23, limits the movement of the lever, 22, and stops, 24 and 25, limit the movement of the operating part, 21. The support, 5, is omitted for the sake of clearness in Figs. 3 to 5. In the rest position, radial arms 7 of the disk, 8, are engaged in recesses of the operating part, 21, and the lever, 22, lies against the stop, 23. Consequently the way is clear 100 105 110 115

for the arm, 7^a to move in the direction of the arrow (Fig. 3) during the ascent of the rod, 4. If now the rod, 4, be raised by the diaphragm, the arm 7^a will slide up in the direction of the arrow. When the arm, 7^a has been raised (as shown in Fig. 4) to a height such that the triangular point of the operating part, 21, is no longer held back by it, the said part, 21, is tipped over by its weight, 28, against the stop 25 and assumes the position shown in Fig. 4. The arm, 7^a has then left the right-hand side of the triangular point and attained its highest position. When the movement is in the downward direction, the arm 7^a slides down along the left hand side of the triangle (Fig. 5) into the position which was previously occupied by the arm 7, that is to say, the rod, 4, and with it the plug, 13, has been rotated through an angle, equal in the example shown, to one-sixth of a complete revolution. The cock is now opened or closed as the case may be. The arm 7^b which comes into operation after the arm 7^a is at first able to slide down without hindrance, but when it reaches the lower position (Fig. 5), it presses the lower end of the lever, 22, in the direction of the arrow and slides past it into its seat. The lever, 22, is moved back by its tipping weight, 29, and the parts have returned into the position shown in Fig. 3, except that arm 7^b is now occupying the place previously occupied by arm 7^a. The next pressure impulse in the gas main repeats the operation and on the sixth impulse the arm 7^a returns into its initial position.

From the foregoing it will be seen that all the movements are effected by positive means so that it is impossible in the case of adequate pressure, for insufficient movements to take place.

A valve, 30 (Fig. 2) may be employed in the stead of a cock. In such an arrangement the upward and rotary movements take place as hereinbefore described, the valve being operated so as to close the gas supply, 18, in its lowered position, while the gas has unrestricted access to the pilot jet supply, 17. The upper part of the valve, 30, is formed with a conical valve face, 31, which, when the valve is opened, is moved up against the upper valve seat, 32, so as to prevent escape of gas to the outside. This double valve is raised and lowered by means of the lever, 37, mounted on an axle, 33. The arm, 38, of this lever, 37, carries a counter-weight 34 arranged to fall to the right or to the left and by its preponderance to press the valve, 30, against its lower seat or its upper seat as the case may be. On the upper end, 4^a, of the upward extension of the rod, 4, is a horizontal disk, 35, provided with three pins, 36, 36^a and 36^b, projecting parallel to the axis of the disk and spaced at equal distances in a circle concen-

tric with the disk. As the disk rotates, one or other of these pins happens to be situated under the right or left arm of the lever, 37, so as, in coöperation with the counterweight, 34, to throw the said lever over to the right or to the left and thereby close or open the valve 30 accordingly, that is to say, extinguish or ignite the burner flame. By employing a correspondingly altered arrangement of the pins, different series of burners (day and night burners) can be controlled. This valve arrangement thus effects the same object as the cock hereinbefore described.

If desired, the horizontal cock may be conveniently interposed between the gas supply and the pipes 17 and 18, by means of which a single street (fitted with permanent pilot jets) may be lighted in the case of fire.

It is to be understood that the word "valve" in the following claims is intended to include a cock.

Having now described my invention, what I claim as new and desire to secure by Letters Patent is:—

1. In apparatus for controlling the gas supply to gas burners at a distance, the combination with a valve controlling said gas supply and a vertically movable rod capable of rotation, of an arm carried by said rod, and a pivoted lever provided with an inclined plane located in the path of said arm and adapted to be struck by said arm, whereby the said rod is rotated in its vertical movement and the said valve is operated, as set forth. 100

2. In apparatus for controlling the gas supply to gas burners at a distance, the combination with a valve controlling said gas supply and a vertically movable rod capable of rotation, of a plurality of arms carried by said rod, and a pivoted lever provided with an inclined plane located in the path common to all of said arms and adapted to be struck by said arms successively, whereby said rod is rotated in its vertical movement and said valve is operated, as set forth. 105

3. In apparatus for controlling the gas supply to gas burners at a distance, the combination with a valve controlling said gas supply, and a vertically movable rod capable of rotation, of a plurality of arms carried by said rod, an operating member having a triangular portion pivoted outside its center of gravity, and a pivoted counterweighted lever having an inclined portion, whereby on the ascent of said rod one of said arms strikes against the inclined portion of said lever whereby said rod is rotated, and whereby on the descent of said rod the same arm is prevented from rotating in the backward direction by the triangular portion of said operating member, as set forth. 115 120

4. In apparatus for controlling the gas supply to gas burners at a distance, the combination with a valve for controlling said 130

gas supply, and a vertically movable rod capable of rotation, of a plurality of arms carried by said rod, means engaging said arms for rotating said rod, and means for transmitting motion from said arms to said valve, as set forth.

5. In apparatus for controlling the gas supply to gas burners at a distance, the combination with a reciprocating valve controlling said gas supply, and a vertically movable rod capable of rotation, of a plurality of arms carried by said rod, means engaging said arms for rotating said rod, and means engaged by said rod in its vertical movement for operating said valve, as set forth.

10. In apparatus for controlling the gas

supply to burners at a distance, the combination with a reciprocating valve controlling said gas supply, and a vertically 20 movable rod capable of rotation, of a plurality of pins carried by said rod, a weighted lever connected to said valve and located over said pins, and means for rotating said rod automatically as it ascends, whereby 25 said lever is struck by said pins alternately on each side of its fulcrum, to open and close said valve as set forth.

In testimony whereof I affix my signature, in presence of two witnesses.
